UNITED STATES PATENT OFFICE.

EDWARD N. JACOBI, OF MILWAUKEE, WISCONSIN, ASSIGNOR, BY MESNE ASSIGNMENTS, TO BRIGGS & STRATTON CORPORATION, OF MILWAUKEE, WISCONSIN, A CORPORATION OF DELAWARE.

HANDLE LOCK.

Application filed April 28, 1921. Serial No. 465,166.

This invention has for its object to provide a lock suitable for use in combination with automobile door handles, electrical switch handles and the like, in which there is a handle member for operating locking or switching or other mechanism and which may be rendered immovable by a key-controlled locking member.

The main object of the invention is to provide such a key controlled locking member for devices of this character which may be placed in its locking condition without the use of the key.

A further object of the invention is to simplify the construction to make it inexpensive to manufacture and durable and efficient in use.

With the above and other objects in view the invention consists in the handle lock as herein claimed and all equivalents.

Referring to the accompanying drawings in which like characters of reference apply to the same parts in different views:

Fig. 1 is a central sectional view of a handle lock as applied to an automobile door handle member and constructed in accordance with this invention;

Fig. 2 is an end view thereof;

Fig. 3 is a sectional view through the locking bolt;

Fig. 4 is a sectional view through the tumbler cylinder;

Fig. 5 is a sectional view through the twirler;

Fig. 6 is a perspective view of the driver; and,

Fig. 7 is a detail view showing the driver pin in the lock bolt slot.

In these drawings 10 indicates a base adapted to be attached to an automobile door 11 in any desirable manner as by means of screws 12 entering from the inner side of the door. The base forms a bearing for a door handle member 13 having a square shank 14 for operating the usual latch mechanism not shown.

A cylindrical locking bolt 15 passes transversely through the handle member 13 and is capable of projecting therefrom into engagement with a slot 16 in the base to prevent the turning of the handle. The movements of this locking bolt are controlled by a lock cylinder 17 which is rotatably mounted in the handle and operates the locking bolt by

means of a cylindrical driver 18. The longitudinally positioned driver 18 and the transversely positioned lock bolt 15 are so related that turning movements of the former will produce a reciprocation of the latter. This is accomplished by means of a pin 19 projecting from the end of the driver 18 slightly eccentric thereto and fitting in a transverse slot 20 of the locking bolt 15. The slot 20 does not extend entirely across the locking bolt but its end forms a stop against which the pin 19 strikes for limiting the turning movement of the driver to one-half of a turn.

The driving connection between the driver 18 and the lock cylinder 17 consists of a pair of lugs 21 projecting from the end of the driver and fitting within the key slot 22 which extends longitudinally through the lock cylinder.

A spring 22' seated in a pocket in the end of the driver 18 between the lugs 21 bears on the end of the lock cylinder 17 and takes up all play between the parts to prevent rattling, the driver 18 being thus held against the locking bolt 15 and the lock cylinder 17 against a retaining ring 23 which forms a bushing at the end of the handle member through which the lock cylinder projects. A shoulder is formed on the lock cylinder to take this end thrust by its engagement with the retaining ring.

A key 24, when entered through the key slot 22, is adapted to pass through openings of a series of tumbler slides 25 fitting in transverse slots of the lock cylinder and its opposite serrated edges are so formed as to cause said tumblers to be contained within the lock cylinder when the key is fully inserted. This enables the lock cylinder to be turned by means of the key so as to throw the locking bolt.

When the key is withdrawn, however, which may be in either the locking or unlocking position of the locking bolt, the tumblers project into opposite grooves 26 within the handle member. When the key is withdrawn with the locking bolt in the locking position, the tumblers projecting into the grooves 26 effectively prevent the lock cylinder from being turned and therefore prevent the withdrawal of the locking bolt, and consequently the handle member cannot be turned to open the door.

When the grooves 26 are formed with par-

allel sides, as usual, the tumblers projecting therein prevent the lock cylinder from being turned in either direction, whether the locking bolt is in the locking position or in the unlocking position. As shown, however, the grooves have cam surfaces 27 on one side thereof, by the action of which the tumblers will be forced into the lock cylinder when the latter is turned in one direction.

10 The relation of the eccentric pin 19 and the slot of the locking bolt is such that the lock cylinder may only have a half turn, and the cam action for returning the tumblers to the lock cylinder takes place only during the movement of the lock cylinder from the position in which the handle member is unlocked to the position in which the handle member is locked. It will be apparent that on completing the half turn of the lock cylinder in this direction the tumblers again enter the grooves 26, but as no further movement in this direction is permitted by the engagement of the eccentric pin 19 with the stop at the end of the slot of the locking bolt, the cams 27 cannot be made to again withdraw the tumblers, and the lock cylinder is effectively locked against movement in either direction. This movement of the lock cylinder under which the cams act to return the tumblers may be effected without the presence of the key by turning the projecting end of the lock cylinder by hand, but the handle member having been locked by this action can only be unlocked by inserting the key to withdraw the tumblers and then turning the key to withdraw the locking bolt.

40 For convenience in turning the projecting end of the lock cylinder by hand it may be provided with a serrated flange or twirler 28.

When the locking bolt is withdrawn the handle may be freely turned to operate the latch in the usual manner and when it is desired to lock the door it is not necessary to use the key because the turning of the lock cylinder by hand accomplishes that purpose. When locked, however, the door handle cannot be moved until the locking bolt is withdrawn, and this requires the use of the key. The hand locking and key unlocking feature of the invention is not only applicable to automobile door handles and switch handles but is capable of general use where it is desired to facilitate the locking operation by dispensing with the necessity for the use of a key.

It will be noted that the screws 12 are entered through the inside of the door and thread into the base 10, thus making them inaccessible, and this prevents the removal of the base in order to open the door.

A stem 29 has a flat surface 30 to fit a corresponding flat surface in the bore of the handle grip 31 which is held thereon by

means of a screw 32 passing through and countersunk in the end of the grip and threaded in the end of the stem. This makes a neat and ornamental handle that is not liable to work loose, the flat surfaces 70 preventing the grip from turning to thereby release the securing screw.

What I claim as new and desire to secure by Letters Patent is:

1. A movably mounted member, a lock cylinder mounted to turn in the member to lock the handle when turned in one direction and to unlock it when turned in the other direction, means for locking the lock cylinder against turning in the direction for unlocking the member, and a removable key fitting in the lock cylinder for disabling said locking means and for turning the lock cylinder in either direction, said lock cylinder being capable of being turned by hand 75 in the direction for locking the member.

2. A member mounted to turn, a locking bolt for locking the member against turning, a lock cylinder mounted to turn in the member and having operative connection with the locking bolt, tumblers in the lock cylinder for preventing it from turning, a removable key for withdrawing the tumblers and for turning the lock cylinder in one direction for locking the member and in the other direction for unlocking the member, and hand operated means for turning the lock cylinder in the direction for locking the member.

3. A member mounted to turn, a lock cylinder mounted to turn therein to lock the member when turned in one direction and to unlock it when turned in the other direction, means for locking the lock cylinder, a removable key fitting in the lock cylinder to 105 disable said locking means and to turn the lock cylinder, and hand operated means capable of turning the lock cylinder only in the direction for locking the member.

4. A member mounted to turn, a lock bolt 110 passing therethrough, a stationary stop engaged by the lock bolt for locking the member, a lock cylinder mounted to turn in the member and having operative connection with the locking bolt for moving it into locking engagement when turned in one direction and for moving it into unlocking position when turned in the other direction, a tumbler in the lock cylinder, a stop on the member engaged by the tumbler for preventing the turning of the lock cylinder in the direction for unlocking the member, a cam on the member for returning the tumbler when the lock cylinder is turned in the other direction, and a key fitting in the lock cylinder for withdrawing the tumbler from engagement with the stop and for turning the lock cylinder in either direction, said lock cylinder being capable of being turned by hand 115 in the direction for locking the member.

5. A member mounted to turn, a locking bolt passing therethrough and provided with a transverse slot terminating in a stop, a stationary stop engaged by the locking bolt for preventing the turning of the member, a cylindrical driver mounted to turn in the member, an eccentrically positioned pin thereon fitting in the slot of the locking bolt and adapted to engage the stop thereof for
10 limiting its movement, a lock cylinder

mounted to turn in the member and having driving connection with the driver, tumblers in the lock cylinder for engaging the member, and a key fitting in the lock cylinder for withdrawing the tumblers and for turning the lock cylinder and the driver to operate the locking bolt.

In testimony whereof I affix my signature.

EDWARD N. JACOBI.
